(57) **CLAIM**

I claim the ornamental design for a dog bowl, as shown and described.

DESCRIPTION

FIG. 1 is a perspective view of a dog bowl showing the claimed design;

FIG. 2 is a top plan view thereof;

FIG. 3 is a rear elevational view thereof;

FIG. 4 is a bottom plan view thereof;

FIG. 5 is a right side view thereof;

FIG. 6 is a front elevational view thereof; and,

FIG. 7 is a left side view thereof.

The broken lines in the drawings depict portions of the dog bowl that form no part of the design claim but are shown for illustrative purposes.

1 Claim, 7 Drawing Sheets
